LEO E. RUSH, OF INDIANAPOLIS, INDIANA

PUMP

Application filed September 4, 1926. Serial No. 133,619.

This invention relates to a visible dispensing device such as a dispensing pump mechanism.

One chief object of this invention is to provide means in or on a visible pump which will permit more accurate reading of the capacity thereof than heretofore possible.

Another object of the invention is to construct a pump of but a few parts and these so arranged that the pump is adapted to either discharge for dispensing purposes or imparting and returning purposes but not both at the same time.

One feature of the invention consists in the provision of means whereby the aforesaid differential action is obtainable and it is impossible to dispense any of the liquid in the dispenser when the same is locked.

The full nature of the invention will be understood from the accompanying drawings and the following description and claim:

In the drawings Fig. 1 is an elevational view of a pump. Fig. 2 is an enlarged vertical sectional view of the dispensing and controlling mechanism including the measuring reservoir. Fig. 3 is a transverse sectional view taken on line 3-3 of Fig. 2 and in the direction of the arrows. Fig. 4 is a section through the swivel joint in the wire conduit.

In the drawings 10 indicates a pump standard which is preferably tubular in character and which terminates in a base 11 pivotally supporting a control valve 12 having a rock shaft 13 extending into the same. Extending outwardly from the base 11 and discharge 14 terminating in a filling hose 15 with a filling nozzle 16. The tubular standard 10 is provided with a foot 17 and the lever 18 through shaft 19 is adapted to actuate the usual pump mechanism for pumping liquid from the reservoir into the dispensing bowl 20 carried by the base. Stationarily mounted by the base 11 or other equivalent means, is a supply conduit 21 which pivotally and slidably supports a cover 22, said cover supporting an illumination unit 23 supplied by the wires 24 which also supply energy to the lighting unit 25 supported by the bracket 26. Unit 25 illuminates the dispensing bowl 20 and the mechanism therein. The cover 22

is slotted as at 27 and said cover also includes an elbow connection 28 which has a pivotally and axially slidable connection with conduit 21 whereby said conduit 21 serves as a pivotal support for the cover 23. Thus, the cover 55 may be elevated slightly so as to remove recess 29 from the supporting plate 30 and after the head has been elevated sufficiently for this removal or unseating, the head is turned angularly for exposing the bolts 31 carried 60 by rods 32 which clampingly associate the base 11 with the head 30. Herein the head plate or top 30 is shown provided with an annular flange 33 which peripherally encloses the upper end of the tubular reservoir 65 20, while the lower end is receivable by the annular recess 34 formed in the upper part of the base 11. The upper part of the chamber thus formed is closed by a cover plate 35, access to all of the foregoing being had by 70 elevating and tilting laterally the head or closure 22 for exposing the several parts. In order to protect all of the foregoing suitable guard means in the form of wire mesh 36 may be supplied. A swivel joint 9 is included in 75 conduit 21.

Extending upwardly from the pump and being positioned beneath the reservoir 20 there is a supply pipe 37 which communicates with the pump discharge and said supply pipe 37 is centrally positioned and extends upwardly and terminates in a valve head 38 including a valve port 39 normally closed by a valve 40 seatable by gravity and opened by the pressure of the liquid supplied 80 from the line 37 when the pump is actuated. The valve head 38 discharges into a combination deflector and outlet 41 having the deflecting head or skirt 42 and the outlet 43. The valve 40, by reason of the action of gravity thereon, really serves as a check valve. Concentric with the supply tube 37 is an overflow tube 45 having an upper end positioned beneath the discharge 43 of the supply connection. The lower end of the overflow tube 45 discharges into the overflow or draining chamber 46 formed in the base 11 and said chamber has normally free communication with the return pipe 47 which returns all of the overflow and the drain to the 100

reservoir connected to the pump. When it is desired to fill the tank or reservoir 20, the pump mechanism is actuated and the liquid is discharged into said tank until such time 5 as the same overflows into tube 45 and is returned to the reservoir through chamber 46 and line 47. When this condition occurs the operator ceases to manipulate the pump and engages the control valve handle 12 for rocking shaft 13 either to the right or to the left. Shaft 13 within the reservoir and head 20 carries a cross bar 50, each end of which is receivable by a socket 51 formed by a yoke portion and a pin 52, said socket being 10 formed as a part of a valve stem, the valve body being indicated at 53 and the stem being extended as at 54, and associated therewith is a seating spring 55. A removable seat forming member 56 is engageable by the valve and the same includes the discharge ports 57. Thus, when the rock shaft 13 is tilted counterclockwise the draining valve 53 is opened and communication is had with the draining reservoir 46 and conduit 47. 15 Thus, all of the liquid trapped in the dispensing tank 20 will be returned to the reservoir for further use. The other end of the cross bar 50 supports a similar valve construction, and said valve arrangement provides communication between the dispensing chamber 60 and the measuring tank 20, the former communicating directly with outlet 14 and discharge line 15. It will be apparent, therefore, that when the valve controlling chamber 60 is opened by actuating handle 12 to tilt shaft 13 clockwise, the draining chamber 46 is cut off from the measuring reservoir or tank 20 while the latter is in free communication with the dispensing chamber 20. 20 Conversely, when the rock shaft is reversely tilted none of the liquid in the measuring chamber 20 will be dispensed but the same will be discharged or returned to the supply reservoir. 25 To insure accurate reading a suitable gage construction is provided and herein the same consists of a plurality of individual markers or gage lines which are each rigidly mounted on the overflow tube for convenience and 30 each completely circles the same so that the scale reading is visible from all sides of the tank and simultaneously. In the upper portion of Fig. 2 one form of level indicator is shown, while in the lower portion of the same figure another form is illustrated. The first form consists of a spring ring 65 having a parting 66 and said spring ring is seatable in the annular groove 67 formed at the proper level in the overflow pipe. This indicates a 35 particular capacity of liquid which would be trapped between the mouth of the overflow pipe or zero level and said gage point. 40 Another form of gage mark consists of an angle plate or strap having a cylindrical portion 68 and a flanged portion 69, the same

being parted and secured together by the clamping mechanism 70.

In viewing the gage marks in order to determine the capacity to be dispensed and determine the time or instant that the handle 12 should be shifted from one position to the other or into neutral position, as shown in Fig. 1, the level of the liquid is compared with the particular or selected gage indicator. It has been found that in viewing the latter through the liquid before the level has descended to the same, there is a secondary image formed on the lever of the liquid and of said gage, as well as the true image of said gage. As the liquid level lowers the first mentioned image approaches the true image so that as the secondary image gradually assumes a smaller radius, the gage being circular, it approaches the real object or image and when the two coincide the true level is obtained. In order to permit handle 12 to be neutrally positioned a relatively loose connection is provided for the two similar but differentially operable valves so that both valves will remain seated when the valve control is in neutral position and a positive movement in either direction will open the respective valve control desired to be actuated. This provision is made so that in dispensing a smaller quantity than the capacity of the chamber 20 the remainder need not necessarily be discharged to the reservoir, but may be held therein until another customer approaches. The tank is thereupon filled to the overflow level and the desired quantity dispensed from the tank. The device is thus so arranged that when the handle is positioned so that the differential valve controlling the communication between the dispensing tank 20 and the overflow or discharge chamber 46, is open, said handle can be locked and this thus assures that there will be no liquid held in the dispensing tank 20 for theft or to be returned to the supply reservoir. 110

The invention claimed is:

In a dispensing device, the combination with a visible bowl, a cover therefor, an illuminating device carried by the cover, an upright tube member extending alongside said bowl and having a slidably and pivoted connection with the cover and a conductor housed within said member and connecting said illuminating device with a source of current. 115

In witness whereof I have hereunto affixed my signature.

LEO E. RUSH.
